HAIR CLIPPERS

Ernest D. Maloy, Cedar Rapids, Iowa

Application May 12, 1952, Serial No. 287,331

8 Claims. (Cl. 30—202)

This invention relates to barbers' tools and has particular relation to motor driven clippers for cutting hair.

It is the practice, in many homes, particularly in large families, for members of the family to cut each other's hair. Most such hair cuts are rough in appearance when cut by such unskilled operators because of the difficulty in feathering or tapering the cut.

It has been proposed that the comb of motor driven shears be made adjustable or variable in thickness so that the operator may vary the cut manually, but such devices are not satisfactory for the reason that the adjustment must necessarily be by steps, with the resulting hair cut still rough.

It is one of the main objects of my invention to provide means for tapering or varying the depth of cut in cutting hair, which means will provide a smooth adjustment of the depth of cut from minimum to maximum without "steps" or roughness.

Another object of the invention is to provide motor driven depth of cut adjusting means for clippers.

Still another object of the invention is to provide a depth of cut adjusting means which will be in synchronization with the rate of movement of clippers over the head.

A further object of the invention is to provide novel means for manually disengaging an automatic hair tapering mechanism and effectively locking the "length of cut" adjustment at any time.

Another main object of the invention is to provide a hair clipping device particularly suited for use by unskilled operators.

Other and further features and objects of the invention will be more apparent to those skilled in the art upon a consideration of the accompanying drawings and following specifications, wherein is disclosed a single exemplary embodiment of the invention, with the understanding, however, that such changes may be made therein as fall within the scope of the appended claims, without departing from the spirit of the invention.

In said drawings:

Figure 1 is a view, generally in top elevation, of the head of a hair-clipping device embodying my invention. A cover and certain other parts of the mechanism have been removed to better illustrate the comb adjusting mechanism with which this invention is more particularly concerned.

Figure 2 is a vertical, longitudinal section taken through the cutting head of the clipper generally along the line 2—2 of Figure 1.

Figure 3 is a plan view of the cutting head, similar to Figure 1 but illustrating the cutter or movable blade actuating mechanism.

Figure 4 is a view in vertical longitudinal section of the cutting head as taken generally along the line 4—4 of Figure 1.

Figure 5 is a fragmentary sectional view of the comb plate and its mounting as taken along the line 5—5 of Figure 2.

Figure 6 is a side elevational view of a hair clipping

2

device embodying my invention and illustrating, in particular, the external portion of the mechanism for adjusting the tapering comb.

Figure 7 is a fragmentary view of the head of the device of Figure 6, illustrating the position of the comb and the external actuating mechanism as it would appear when taking the shortest cut possible as in the start of a stroke at the base of the hair line, and

Figure 8 is a similar fragmentary view in side elevation of the cutting head, but illustrating the position of the comb and the operating mechanism as it would appear at the end of a stroke in which the hair has been tapered from a minimum to a maximum length.

Referring now to the drawings in which my invention is shown in connection with a more or less conventional driving mechanism powered by an electric motor; the electric motor (not shown) is mounted within the handle 10, an extension shaft 12 of the motor extending longitudinally through a bushing 13 into the head 11 on the forward end of the handle.

The cutter blade 16, which is mounted for transverse reciprocating movement at the forward end of the head 11, in contact with the upper surface of the comb plate 17, is caused to reciprocate transversely by power supplied from the electric motor through the following elements. A worm 18, affixed to the motor shaft 12, is meshed with a worm gear 19 mounted for free rotation on the vertical stub shaft 21. A cam 22 affixed to the top of the worm gear 19 serves to drive the rocker arm 23 through the clipper pitman 24 which is pivotally connected thereto by means of the pivot pin 26. The rocker arm is pivotally mounted on the pivot stud 27, and sealed by felt wipers 25. The felts 25 wipe the member 23 to seal the gear box and keep fuzz and hair from entering the chamber in which the worm gears are mounted.

The end of the rocker arm is received in a socket or slot 28 in the cutter blade 16 whereby movement of the rocker arm results in rapid reciprocation of the cutter blade. This cutter blade is urged into firm contact with the comb plate 17 by means of the leaf spring 29 which rides in the transverse groove 30 in the upper face of the cutter blade.

The comb plate 17, which may be extended or retracted relative to the cutter blade, is slideably mounted on the angularly disposed underside of the head. The slides 31, best shown in Figure 5, are secured to the inner recessed surface of the comb plate 17 by screws 32, and these slides are dovetailed, as indicated at 33, into the side walls of the head for sliding movement therein. A rack 34, provided between the slides 31, is engaged by the gear sector 36. This gear sector is affixed to the rotatably mounted transverse sector shaft 37 which is caused to rock by power supplied from the motor through the worm 18 and the following mechanism.

A worm gear 38, meshed with the drive worm 18, is mounted for free rotation on the transverse supporting shaft 39. A worm 41 (Figure 2), also mounted on the shaft 39, is secured to the worm gear 38 for rotation therewith by any suitable means, such as a tooth and groove connection, not shown. An intermediate worm gear 42, meshed with the worm 41, is carried by the vertically positioned stub shaft 43 along with the final worm 44. The worm 44 is slideable on the stub shaft 43 to permit disengagement from the intermediate worm gear 42 with which it is engaged by means of a dog-toothed clutch 46. Movement of the worm 44 away from the worm gear 42 is limited by the snap ring 47.

The final driven gear 48, which meshes with the final worm 44, is pinned to the transverse crank shaft 49 which extends through a bushing 51 in the side wall of the head 11. A circular crank plate 52, threadedly engaged on the outer end of the crank shaft, and preferably

knurled on its peripheral surface, has a socket 53 in the outer face thereof spaced from the axis of the shaft. The crank pin 54, which is affixed to the end of the comb pitman 56, is received in the socket 53. The crank pin is normally held in position by the resilience of the pitman and the rocker arm 57 to which the pitman is pivotally connected at 58.

The rocker arm 57 is affixed to the threaded outer end of the transverse rocker shaft by means of the nut 59 and prevented from turning by means of a key or a prick-punched indentation, as indicated at 61.

The comb pitman 56 may be detached from the crank plate by springing the pitman outwardly. When detached, the pitman may be used to manually position the comb to secure any desired length of cut. For this purpose a plurality of sockets, as indicated at 62, are adapted to selectively receive the crank pin 54. Figure 6 illustrates, by dotted lines, the position of the pitman 56 when adjusted in this manner. Thus the clipper may be operated in the manner of a conventional type clipper, except that it may be readily adjusted to cut hair to any desired uniform length within the adjustable range of the comb plate.

The interior mechanism of the clipper head is enclosed by the cover plate 64 which is secured in position by screws 66.

The functioning of the cutter blade actuating mechanism is more or less conventional, but the comb plate adjusting mechanism, which operates in conjunction with the cutter drive, or independently as desired, provides a hair clipping device which is particularly adapted for home use by an unskilled operator.

However, the novel features of my device make it just as valuable to the professional barber.

In use, and with the comb pitman engaged to the crank plate, the comb will be reciprocated, fore and aft, at a speed determined by the rotation of the crank plate 52. The gear train 38, 41, 42, 44, 48, which drives the crank plate 52 from the motor worm 18 is preferably designed to provide an operating cycle of from two to four seconds, although slower speeds as well as speeds in excess of one revolution per second are operable. Thus the operator, in trimming a subject's hair, starts a cutting stroke at the base of the hair line, as shown at 67 in Figure 7, when the comb plate is in its fully retracted position. As the operator moves the clippers upwardly, the comb plate is fed outwardly for a period of approximately two seconds or three and even the most unskilled operator can quickly learn to synchronize his movements with those of the comb plate.

During the return portion of each cycle, the comb plate is retracted for a like period of two or three seconds during which period the operator may reposition the clippers for the next stroke.

Figure 8 illustrates the manner in which the comb plate is extended as the clipper is moved upwardly whereby a cut is provided which tapers smoothly from a minimum at the hair line to a maximum at the top of the stroke.

It should be here noted that the motion of the comb plate, driven by a pitman and constant-speed crank plate, corresponds to a sine wave. Because of this, the rate of movement of the comb plate is relatively slow, both at the beginning and at the end of each stroke. Thus the operator has better opportunity to control the cut at these points which are naturally relatively more critical. Of primary importance is the fact that the operator is not required to lift the clippers before the comb plate starts to retract in order to avoid a rough line at the upper end of the tapered cut. The operator may slide the clippers downward over the scalp during the retracting portion of a cycle to place the clippers in position to even up a cut on the next upward stroke, or lift the clippers off the scale or slide them to a new position to start a new cut. He has several seconds to do this.

As stated before, the automatic comb feed may be dis-

engaged by springing the crank pin out of the crank plate. This may be accomplished in another and, for some purposes, more convenient manner.

The crank plate 52, as stated before, is preferably rotated at a speed of approximately one revolution in four seconds, which is slow enough to permit the user, at any point during a cycle of operation, to rotate the crank plate manually.

This may be accomplished by movement of the thumb against the crank plate in the direction indicated by the arrow. The movement must be at a speed sufficiently greater than the normal driven speed in order that pressure will be exerted upwardly on the final worm 44 to disengage the dog-tooth clutch 46. Immediately the clutch is disengaged, the worm will cease to rotate and no further movement of the thumb will be required in order to prevent further automatic movement of the comb plate. The snap ring 47 limits the movement of the worm 44 which effectively locks the crank plate and comb plate as long as the user maintains pressure on the crank plate as described.

Both the comb plate and cutter blade may be quickly removed for sterilizing. The pitman 56 may be disengaged from the crank plate to permit the rocker arm 57 to be moved rearwardly. Sufficient movement results in disengagement of the gear sector 36 from the rack 34 and the comb plate may be completely removed. The cutter blade will be released at the same time.

Although I have described a specific embodiment of my invention, it is apparent that modifications thereof may be made by those skilled in the art. Such modifications may be made without departing from the spirit and scope of my invention as set forth in the appended claims.

I claim as my invention:

1. In a hair clipper having a head, a cutter blade mounted thereon for transverse reciprocation, and means for reciprocating the cutter blade; a comb plate slideably mounted on the head for longitudinal reciprocation relative to the cutter blade, and means for reciprocating said comb plate, said latter means including a crank member and means operatively connecting the crank member and the comb plate, said means for reciprocating the comb plate being arranged to reciprocate the comb plate at a substantially slower rate of speed than the cutter blade, and a driving mechanism for driving said means for reciprocating said comb plate inwardly and outwardly at regulated rates, said driving mechanism being operatively connected with the means for reciprocating the cutter blade.

2. In a hair clipper having a head, a cutter blade mounted thereon for transverse reciprocation, a motor, and means powered by the motor for reciprocating the cutter blade; a comb plate slideably mounted on the head for longitudinal reciprocation relative to the cutter blade, and means for reciprocating said comb plate, said means including a crank member and means operatively connecting the crank member and the comb plate, and a driving mechanism operatively connected with the motor and arranged to rotate the crank member at a speed not in excess of one revolution per second.

3. In a hair clipper of the character described having a cutter blade and a comb plate mounted for longitudinal reciprocation relative thereto for the purpose of controlling the distance between the cutting edges of the cutter blade and a hair bearing surface; a crank plate and means, including a pitman, operatively disposed between the crank plate and the comb plate translating rotary motion of the crank into reciprocating motion of the comb plate, a motor, and means adapted to drive the crank plate from the motor at reduced speed, said means including a worm gear, a floating worm engaged therewith and clutch members normally in engagement to drive the worm, the said worm, worm gear and clutch being so arranged that normal driving movement urges the clutch members into engagement and whereby manual acceleration of the crank plate by

the user will float the worm and disengage the clutch members to thereby stop the crank plate at any point during a cycle of operation.

4. In a device of the character described comprising a head having a cutting mechanism, a motor operatively connected therewith, a comb plate adjustably positioned relative to the cutting mechanism for controlling the position of the cutting mechanism relative to a hair-bearing surface and means providing a power-driven, cyclic operation ranging from a minimum to a maximum adjustment of the comb, said means including speed reduction mechanism driven by the motor, a floating worm, clutch means operatively connecting the speed reduction mechanism and the worm and disengageable by sliding movement of the worm, a worm gear in engagement with said worm, a crank plate driven thereby, and means including a pitman operatively connecting the crank means and the comb plate.

5. In a device of the character described comprising a head having a cutting mechanism, a motor operatively connected therewith and a comb plate adjustably positioned relative to the cutting mechanism; drive means providing a cyclic operation ranging from a minimum to a maximum adjustment of the comb, said drive means including speed reduction mechanism driven by the motor, a crank, a pitman and a rocker arm operatively connected between the crank and the comb plate, and manually operable clutch means disposed to optionally disengage a portion of said drive means at any point during a cycle of operation.

6. In a device of the character described comprising a head having cutting mechanism, a motor operatively connected therewith and a comb plate positioned relative to the cutting mechanism for the purpose of spacing the cutting mechanism away from a hair-bearing surface; means for adjusting the relation of the comb plate to the cutting mechanism, and drive means for continuously moving the comb plate through complete cycles of adjustment, each

cycle ranging from minimum through maximum limits of adjustment and each cycle requiring a period of time in excess of one second for completion.

7. In a device of the character described comprising a motor, a head having cutting mechanism, and a comb plate adjustably positioned relative to the cutting mechanism for the purpose of spacing the cutting mechanism away from a hair-bearing surface; means for driving the comb plate through a complete cycle of adjustment from minimum through maximum adjustment, said drive means including a crank and pitman whereby translation of rotary motion by the crank into linear movement by the pitman results in a relative slow rate of change of adjustment of the comb plate when approaching the minimum and maximum limits of adjustment.

8. In hair clippers, a comb, and a cutter blade in face-to-face contact with said comb and adapted for reciprocation thereon to cut hair with a shearing action, the comb being sharp at the forward edge and thick at the rear ends of the teeth, means for reciprocating the cutter, means for moving the comb outwardly for a given period of time to increase the spacing between cutter and scalp as the operator moves the clipper upwardly on the head, and means for retracting the comb through a like period of time to enable the operator to position the clipper for the next cutting stroke, the timing of the movement of the comb being determined and maintained in known and constant periods to enable the operator to accurately pace his cutting and positioning movements.
